UNITED STATES PATENT OFFICE.

FRANKLIN MOHR, OF EAST ORANGE, NEW JERSEY, ASSIGNOR TO WESTERN ELECTRIC COMPANY, INCORPORATED, OF NEW YORK, N. Y., A CORPORATION OF NEW YORK.

TRANSMISSION SYSTEM.

Application filed May 26, 1926. Serial No. 111,725.

This invention relates to transmission systems, and more especially to systems for the transmission of images from one point to another by the use of electricity.

5 The object of the invention is to increase the efficiency and to improve the serviceability of transmission systems of this general character.

It has been proposed to employ frequency 10 modulation in signal transmission systems such for example as shown and claimed in the copending application of M. B. Long, Serial No. 110,910, filed May 22, 1926.

In accordance with the present invention, 15 however, there is provided an arrangement employing frequency modulations wherein the current for reproducing the picture is the resultant of the output currents of two demodulators, one of which currents varies 20 as the frequency and the other of which is independent of frequency. Furthermore, there are provided two demodulators so connected that the output currents due to changes in transmission level are neutralized, 25 the output current of one demodulator due to frequency changes only affecting the light valve to reproduce the picture.

The drawing is a diagrammatic showing 30 of a picture transmission system including a transmitting and a reproducing station and embodying the features of this invention.

The following are two of the various methods of transmitting signals by means of carrier current. One is to employ the signal 35 for the purpose of modulating the amplitude of the carrier wave, and the other is to employ the signal current for modulating the frequency of the carrier wave. The system disclosed herein is of the second type. 40 A carrier current is generated at the transmitting station and in a suitable manner modulated as to its frequency by means of a current which represents the tone values of the picture. The frequency modulated 45 carrier wave is transmitted over the line to the receiving station, where it is demodulated and applied to some device such as a light valve.

Under ideal conditions, the carrier current 50 will have a uniform amplitude and a frequency which represents exactly the varying tone values of the picture. This carrier wave at the receiving station may be translated into a current in which the amplitude

varies as the frequency of the received wave, 55 or, in other words, as the tone values of the picture. It is well known, however, that difficulty is had in maintaining the transmission system uniform at all times. That is to say, the so-called transmission level 60 varies due to conditions which cannot be easily controlled. A variation in the transmission level means a variation in the amplitude of the transmitted current, which, unless accounted for, will make itself felt 65 in the reproduced picture.

The present invention contemplates the use of a receiving equipment in which such 70 variations of transmission levels are neutralized or compensated.

Referring particularly to the drawing, there is shown a rotatable and axially movable picture drum 2 mounted on a shaft 1 at the transmitting station. A film or transparency 3 of the picture is wrapped about 75 the drum 2 and scanned by a beam of light from the source 5 concentrated by a lens 6 upon the surface of the drum 2. Within the drum 2 is located a photo-electric cell 4. The cell 4 is connected across the terminals of a resistance 8 in series with a source 90 of photo-electric potential 61 for the photo-electric current. The resistance 8 is connected across the input circuit of a picture amplifier PA. The amplifier PA consists 85 of a thermionic discharge device 7 having a filamentary cathode 10, a plate anode 12, and a control electrode 11. The resistance 8 is connected across the control electrode 11 and the filament 10. A battery 9 is connected 90 so as to maintain the electrode 11 at a desired potential.

The output circuit of the amplifier PA includes the electrodes 10 and 12 and the source of space current 13. This circuit is 95 connected across the terminals of a winding 16 of a transformer 14. If desirable other stages of amplification of the resistance type may be added.

The transformer 14 is a part of an oscillating circuit including the oscillator O. The oscillator O comprises a thermionic discharge device 21 having a filamentary cathode 22, a plate anode 24, and a control grid 23. The input circuit of the oscillator 100 includes the filament 22, the inductive winding 17, and the grid electrode 23. The output circuit of the oscillator O has one branch 105

including the plate 24, choke coil 27, battery 26, and the filament 22. This branch provides space current for the oscillator, the choke coil 27 serving to prevent high frequency currents from flowing therein. Another branch of the output circuit includes the condenser 28 and impedance elements 30, 31 and 32. Still another branch includes the condenser 28, impedance element 30, resistance 20, inductive winding 15, and condensers 18 and 19 and variable impedance element 16. This latter branch serves as a feedback circuit for causing the device 21 to oscillate. The condenser 18 may be variable for the purpose of tuning the circuit to secure the desired frequency. The condenser 19 restricts the current from the source 13 to the plate circuit of the amplifier PA.

20 The terminals of the impedance element 32 may be connected to a transmission equalizer TE of any suitable design. The equalizer TE is connected to the transmission line L. The purpose of the equalizer TE is to give 25 a uniform amplitude for the various frequencies. If necessary, the transmission line L may pass through a repeating station RS, at which there is located a repeating amplifier RA controlled in any well known and 30 suitable manner by a rectifier R and a gain control arrangement GC.

At the receiving station, the transmission line L is connected to a pair of networks 37 and 58. The network 57 may be of any 35 suitable design and, as illustrated, includes two series loops 33 and 34 each comprising an inductive element and a condenser. The network 57 also includes a pair of shunt condensers 35 and 36.

40 The other network 58 comprises two resistances 59 and 60, the first of which may be variable.

The output end of the network 57 is connected across a resistance 41. The terminals 45 of the resistance 41 are connected to the input circuit of a demodulator D₁. The demodulator D₁ consists of a thermionic discharge device 37 having a filament 38, a plate 40, and a grid electrode 39. The grid electrode 39 is maintained at any desired 50 potential by means of the battery 47. The output circuit of the demodulator D₁ includes the plate electrode 40, the space current source 50, and the filament 38. This 55 circuit is connected across the terminals of a high resistance 51.

The second network 58 is connected to a 60 resistance 46. The resistance 46 is connected across the input circuit of a second demodulator D₂. This demodulator comprises a thermionic discharge vacuum tube 42 having a filament 43, plate 45, and a grid electrode 44. Battery 47 also provides a biasing potential for the grid 44. In similar 65 manner, the output circuit of the demodula-

tor D₂ includes the battery 50 and is connected across the terminals of a high resistance 52.

The condensers 48 and 49 are connected across the output circuits of the respective 70 demodulators.

A light valve V of any well known type, such as the vibrating string valve, has its terminals connected across the output circuits of the two demodulators D₁ and D₂, 75 as illustrated. The valve V serves to control a beam of light from the source 53, through the lenses 54 and 55, to the surface of the reproducing drum 56.

The operation of the system will now be 80 described. A transparency of film of the picture to be transmitted is mounted upon the drum 2 and scanned by the optical system. The variable current flowing through the resistance 8 causes the potential of the 85 grid electrode 11 of the amplifier PA to vary. Thus, the impedance of the plate circuit of the amplifier is varied, causing a corresponding variation in the current flowing through the winding 16 of the reactive device 14. The device 14 is so designed that the reactance thereof varies with the intensity of the current flowing in the winding 16. This variation in reactance results in a corresponding variation in the frequency 95 of the oscillating current generated by the oscillator O. The result is, therefore, that the carrier current impressed upon the line L is one the frequency of which varies in accordance with the tone values of the 100 picture.

At the repeating station RS, the carrier current transmitted over the line is repeated and amplified in the well known manner.

At the receiving station, the transmitted 105 carrier current having its frequency modulated is impressed upon the network 57. The characteristic of the network 57 is such that the output current therefrom varies in amplitude in proportion to the variation in 110 frequency of the current impressed thereon. In this manner the carrier current has been translated into one having an amplitude which varies in accordance with the tone values of the picture. This variable amplitude current flowing through the resistance 41 causes a corresponding variation in the potential of the grid electrode 39 of the demodulator D₁. In the well known manner 115 the demodulator D₁ produces in its output circuit a current which varies in proportion to the variation of the grid potential.

The transmitted carrier current is also impressed upon the network 58 including resistances 59 and 60. The network 58 is 120 independent of frequency, and accordingly the amplitude of the current is not altered due to a change of frequency. The value of the current flowing through the resistance 46 determines the potential of the grid elec- 125 130

trode 44 of the demodulator D_2 . The potential of this grid electrode in turn determines the amplitude of the current flowing in the plate circuit of the demodulator D_2 .

5 For ideal conditions, the amplitude of the current flowing in the transmission line will not vary. That is to say, the transmission level will remain constant. Under these conditions, the range of potential variation 10 of the grid electrode 44 remains substantially constant, and accordingly the amplitude of the current in the output circuit of the demodulator D_2 is substantially constant.

The circuits are so adjusted that the value 15 of the current in the output circuit of the demodulator D_2 is equal to the current which flows in the output circuit of the demodulator D_1 for a given arbitrary frequency of the transmitted current. Ordinarily, this 20 arbitrarily selected frequency will be the lowest one in the useful scale of frequencies. In other words, it will be the frequency which is produced due to an extreme value of tone to be found in the picture transmitted. Since the output currents of the demodulators are equal for an extreme value 25 of frequency, they may be made to balance or neutralize each other to give a completely closed or a completely open condition of 30 the light valve V , as desired. For other values of frequency in the useful scale, it follows that the output current of the demodulator D_1 exceeds that of the demodulator D_2 by a corresponding amount and accordingly 35 the resultant current will determine the operation of the valve V , the amount of operation being a measure of the frequency of the transmitted current, or, in other words, a measure of the tone value of 40 the picture being transmitted.

Referring to the output circuit of the demodulator D_1 , it will be noted that for the arbitrary value of frequency mentioned, a current of a given amplitude flows in 45 the circuit 40, P , 51, P_1 , 50, 38. Due to this current, the potential of the point P is raised to a certain value with respect to the potential of the point P_1 . At the same time, a current of equal amplitude is flowing in 50 the circuit 45, P_2 , 52, P_1 , 50, 43. Accordingly, the potential of the point P_2 with respect to the point P_1 is the same as that for the point P . Therefore, no current will flow through the circuit including the string 55 of the light valve V . As the frequency increases, however, and the current in the output circuit of D_1 correspondingly exceeds that of the current in the output circuit of D_2 , the potential of point P with respect to point P_2 increases. This causes a current 60 to flow through the string of the light valve V for actuating the same to govern the intensity of the beam of light striking the drum 56.

65 While the transmission level remains con-

stant under ideal conditions, it is to be expected that in practice the transmission level will vary due to conditions not easily controlled. It is to compensate for these variations of amplitude that the demodulator D_2 is particularly adapted. When a given variation in amplitude occurs, due to a change in transmission level, a corresponding change takes place in the potential of the grid electrode 39 of the demodulator D_1 . 70 This in turn produces a corresponding change in the amplitude of the current flowing in resistance 51. It may be said, therefore, that the output current of the demodulator D_1 is made up of two components, one 75 of which is proportional to the frequency of the transmitted carrier current and the other of which is proportional to the amplitude or to the transmission level.

The change of amplitude or of transmission level also produces a corresponding change in the potential of the grid 44 of the demodulator D_2 . This results in a change in the current flowing in a resistance 52. These changes, namely that in the amplitude of the 80 current in the resistance 51 and that in the amplitude of the current in the resistance 52, are substantially equal. Therefore, the resultant current flowing in the light valve V is 85 substantially free from the changes in the transmission level.

It may be noted that both the gain control device GC at the repeater station and the apparatus at the terminal station serve for the same general purpose. The gain control 100 device GC may be considered as giving supplemental regulation.

It will be understood that the picture transmission equipment which has only been illustrated schematically, may be of any well known construction. For a more complete understanding of the details of apparatus of this character, reference is made to the Patent of Horton et al., No. 1,606,227 patented Nov. 9, 1926.

110 What is claimed is:

1. In an image transmission system, transmitting and receiving stations, means at the transmitting station for generating an alternating carrier current, means for modulating the frequency of said current in accordance with the characteristics of a picture or object, a line for transmitting the modulated carrier from the transmitting station to the receiving station, two demodulators at the receiving station having output circuits and being responsive to the frequency modulated carrier, the current in one output circuit being proportional to variations in the amplitude of the transmitted 115 current, the current in the other output circuit being proportional both to the amplitude and frequency of the transmitted current, a light translating device, means for 120 opposingly connecting the output circuits of 125

130

the said two demodulators, and means for impressing the resultant output current from the said demodulators upon the said light translating device.

5 2. In an image transmission system, a transmitting station having means for generating an alternating carrier current, means for modulating the frequency of said current in accordance with the tone values of a picture or object, a receiving station, means for transmitting the modulated carrier current from the transmitting station to the receiving station, a demodulator having an output circuit and responsive to the transmitted carrier current to produce in said circuit a current proportional only to the amplitude of the transmitted current, a second demodulator having an output circuit and responsive to the transmitted current to produce in 10 its output circuit a current proportional both to the amplitude and frequency of the transmitted current, a light controlling device differentially connected to both output circuits whereby the current flowing in said 15 valve due to currents in said output circuits is proportional only to said frequency, and means controlled by said valve for reproducing the picture.

3. In an image transmission system, a transmitting station having means for generating an alternating carrier current, means for modulating the frequency of said current in accordance with the tone values of a picture or object, a receiving station, means 20 for transmitting the modulated carrier current from the transmitting station to the receiving station, two demodulators having output circuits one responsive to the transmitted current to produce in its output circuit a current having two components, one component proportional to the amplitude and the other proportional to the frequency of the transmitted current, the other demodulator responsive to the transmitted current to produce a current in its output circuit which is proportional to the amplitude but independent of the frequency of the transmitted current, a circuit connected to both of said output circuits for causing the 25 current in the second output circuit to neutralize the component of the current of the first output circuit which is proportional to amplitude, and to transmit to a light translating device the resulting current which is 30 proportional to frequency, and a light valve translating device having impressed thereon the said resulting current from the two demodulators.

4. The combination in an image transmission system, of means for generating an oscillatory carrier current, means for modulating the frequency of said current in accordance with the characteristics of a picture or object, means for transmitting the 35 modulated current, a network for receiving

and translating the transmitted current into a current of varying amplitude, a demodulator connected to said network and arranged to produce a current in its output circuit proportional both to said frequency and to the amplitude of the modulated carrier current, a second network for receiving the modulated carrier current but acting independently of the frequency, a second demodulator connected to said second network and arranged to produce in its output circuit a current proportional only to the amplitude of the demodulated carrier current, and a light valve differentially connected in the output circuits of said demodulators.

5. In an electrical signal transmission system, transmitting and receiving stations, means at the transmitting station for generating an alternating carrier current, means for modulating the frequency of said current in accordance with the characteristics of a signal, a line for transmitting the modulated carrier from the transmitting station to the receiving station, two demodulators at the receiving station having output circuits and being responsive to the frequency modulated carrier, the current in one output circuit being proportional to variations in the amplitude of the transmitted current, the current in the other output circuit being proportional both to the amplitude and frequency of the transmitted current, a signal translating device, means for opposingly connecting the output circuits of the said two demodulators, and means for impressing the resultant output current from the said demodulators upon the said signal translating device.

6. In an electrical signal transmission system, a transmitting station having means for generating an alternating carrier current, means for modulating the frequency of said current in accordance with a signal, a receiving station, means for transmitting the modulated carrier current from the transmitting station to the receiving station, two demodulators having output circuits, one responsive to the transmitted current to produce in its output circuit a current having two components, one component proportional to the amplitude and the other proportional to the frequency of the transmitted current, the other demodulator responsive to the transmitted current to produce a current in its output circuit which is proportional to the amplitude but independent of the frequency of the transmitted current, a circuit connected to both of said output circuits for causing the current in the second output circuit to neutralize the component of the current of the first output circuit which is proportional to amplitude and to transmit to a signal translating device the resulting current which is proportional to 130

frequency, and a signal translating device having impressed thereon the said resulting current from the two demodulators.

7. A signal transmission system comprising means for producing a carrier wave the frequency of which is modulated in accordance with the signal, a transmitting medium in which variations in attenuation may take place, means for receiving the modulated carrier wave comprising two paths in parallel relation with respect to the incoming carrier wave which paths are substantially equally responsive to amplitude variations in said wave, a signal reproducing device in

balanced relation with respect to said paths and frequency discriminating means in one of said paths for unbalancing said paths with respect to said signal reproducing device for frequency variations of said wave.

8. A signal transmission system in accordance with claim 1 comprising detecting means for detecting said high frequency wave to produce a low frequency component for operating said signal reproducing device.

In witness whereof, I hereunto subscribe my name this 22 day of May, A. D. 1926.

FRANKLIN MOHR.
